UNITED STATES PATENT OFFICE.

CLARENCE H. HOWARD, OF ST. LOUIS, MISSOURI.

RAILROAD MOTOR-CAR.

No. 813,427.

Specification of Letters Patent.

Patented Feb. 27, 1906.

Application filed December 1, 1905. Serial No. 289,901.

To all whom it may concern:

Be it known that I, CLARENCE H. HOWARD, a citizen of the United States, residing at St. Louis, in the State of Missouri, have invented 5 a new and useful Improvement in Railroad Motor-Cars, of which the following is a specification.

My invention relates particularly to the frame and floor of that class of railroad motor-car which is propelled by gasoline or other suitable motor mounted thereon combined with weed-burning apparatus or otherwise adapted for use in railroad-yards for the handling and transportation or switching of 15 material, and has for its object to provide a light, rigid, and durable car of simple construction.

The invention consists in features of novelty, as hereinafter described and claimed, 20 reference being had to the accompanying drawings, forming part of this specification, whereon—

Figure 1 is a top plan view of a motor-car constructed according to my invention; Fig. 25 2, a side elevation thereof; Fig. 3, a vertical longitudinal section through the frame and floor on line 3 3 in Fig. 1; and Figs. 4 and 5, vertical transverse sections through the same on lines 4 4 and 5 5, respectively, in Fig. 1.

Like letters and numerals of reference denote like parts in all the figures.

a represents my improved motor-car, which, as usual in this class of car, is preferably a flat-car and consists of the frame proper or wheel-frame, which comprises two opposite side and end pieces or sills 1 1', respectively, composed, preferably, of cast-steel continuous and integral throughout and preferably channel-shaped in cross-section, 35 as shown, or the side and end pieces 1 1' may be **H**, **I**, or any other suitable section.

Extending between and preferably flush with the top flanges of the frame 1 1' is the floor 3 of the car *a*, which is composed of cast-45 steel in one piece of suitable thickness and integral with the frame 1 1'. From the floor 3 on its under side and integral therewith project longitudinal webs or ribs 4 and transverse ribs 4', which are disposed at suitable 50 distances apart and intersect each other, respectively, at right angles, the longitudinal ribs 4 being united integrally at their ends to the end pieces 1' and the transverse ribs 4' to the side pieces 1 of the frame, the frame 1 1' 55 and floor 3 with the ribs 4 and 4' thereby

forming a light, homogeneous, and rigid casting integral throughout.

To the side pieces 1 on their under sides are fixed the pedestals 5, having the axle-boxes 6, wheels 7, equalizing-bars 8, with 60 their springs 9 and other appendages all constructed and arranged in the usual well-known manner, the seats 10 for the springs 9 being integral with the side pieces 1.

On the floor 3, near one end thereof, or otherwise located as required, is preferably formed a reinforcing raised portion or bedding surface 11, on which the motor (indicated by dotted lines) is fixed, and through the floor 3 in central longitudinal alinement to the surface 11 and at a suitable distance therefrom is formed an opening 12 for the passage and play therethrough of the sprocket-chains or other device for transmitting the power from the motor to the propelling-gear (not shown) 75 of the car *a*, which is mounted on the under side of the floor 3 in any suitable well-known manner, while through the floor 3, adjacent to the side pieces 1 of the frame, are formed the clearance-openings 13 for the wheels 7 of the 80 car *a*, as shown. In the floor 3, adjacent to its other end or otherwise suitably located, is preferably formed a pocket 14, having its walls integral with the floor 3 and adapted to receive the lower end or foot of a derrick-post 15, (broken away), which is rotatably held within and removable from the pocket 14—that is to say, when the car *a* is used for lifting and transporting material or for hauling and pushing small hand-cars around a 90 railroad-yard the weed-burning apparatus is removed therefrom and the derrick-post 15 inserted at its lower end within the pocket 14, the derrick being operated by hand or by the motor which is used for propelling the car *a* 95 at all times.

When the car *a* is used as a weed-burner, the post 15 is removed from the pocket 14 and the opening of the latter closed by a cover-plate or cap 16, as indicated by dotted 100 lines in Fig. 5.

Suitable strengthening-ribs 17 17' preferably unite the pocket 14 integrally to the under side of the floor 3 and to the ribs 4' and end pieces 1', respectively, of the frame, as 105 shown.

What I claim as my invention, and desire to secure by Letters Patent, is—

In a motor-car of the character described, the combination with a cast-steel wheel- 110

frame integral throughout, of a floor supported by and integral with the said frame, a pocket in the floor adapted to receive a derrick-post, and ribs integral with the floor on its under side, the said ribs being united at their ends integrally to the said frame, substantially as described.

In testimony whereof I have signed my name to this specification in the presence of two subscribing witnesses.

CLARENCE H. HOWARD.
